UNITED STATES PATENT OFFICE

128,267

DESIGN FOR A PRESSING IRON

Clifford Brooks Stevens, Fox Point, and Edward P. Schreyer, Milwaukee, Wis.; said Stevens assignor to said Schreyer

Application May 19, 1941, Serial No. 101,014

Term of patent 14 years

To all whom it may concern:

Be it known that we, Clifford Brooks Stevens and Edward P. Schreyer, residing at Fox Point and Milwaukee, respectively, in the county of Milwaukee and State of Wisconsin, have invented a new, original, and ornamental Design for a Pressing Iron, of which the following is a specification, reference being had to the accompanying drawing, forming part thereof.

In the drawing, in which the handle is shown in dotted lines and in which the characteristic

features of our design are shown in full lines, Fig. 1 is a side elevational view of a pressing iron showing our new design; Fig. 2 is a top plan view thereof; Fig. 3 is a front elevational view; Fig. 4 is a rear elevational view; and Fig. 5 is a reduced bottom plan view.

We claim:

The ornamental design for a pressing iron, substantially as shown and described.

CLIFFORD BROOKS STEVENS.
EDWARD P. SCHREYER.
